UNITED STATES PATENT OFFICE.

MABEL A. C. HENDERSON, OF CHICAGO, ILLINOIS.

HAIR-WAVER.

1,221,447.

Specification of Letters Patent.

Patented Apr. 3, 1917.

Application filed October 25, 1916. Serial No. 127,516.

To all whom it may concern:

Be it known that I, MABEL A. C. HENDERSON, a citizen of the United States, residing at Chicago, in the county of Cook and State of Illinois, have invented certain new and useful Improvements in Hair-Wavers, of which the following is a specification.

My invention relates to devices for waving human hair, the purpose being to produce an appearance sometimes known as "Marcel waves." The object of the invention is to produce a device by which this effect may be quickly and easily produced either by a hair dresser or by the person whose hair is to be waved. On account of the convenience of operation of my device, a person may readily wave the hair of her own head and produce a uniform and natural appearance which would otherwise be difficult, if not impossible, to accomplish.

I accomplish my object by the mechanism illustrated in the accompanying drawings, in which—

Figure 1 is a view of the front of the device.

Fig. 2 is a longitudinal section thereof.

Fig. 3 is a view of the back of the device.

Fig. 4 is an enlarged section on the line 4—4 of Fig. 1.

Fig. 5 is a detail sectional view on the line 5—5, Fig. 3, showing the spring locking device for holding the matrix in the different positions to which it may be shifted.

Fig. 6 is a perspective view illustrating the manner of using the device.

Similar numerals refer to similar parts throughout the several views.

In the form selected to illustrate the invention, there are two side bars, 1, 1 which are arranged parallel to each other and are supported upon a handle 2. These may be regarded as constituting the main frame of the device. Arranged along the opposite edges of the side bars are rows of teeth 3 which receive the strands of the hair between them after the manner of combs. These teeth project from the front of the frame and may assume various shapes as may be desired.

Slidably mounted upon the side bars is a part 4 which, for convenience, I shall refer to as the "matrix." In the preferred form the matrix is convex when viewed from the front, as in Fig. 1, and in the present instance, when viewed in cross-section as in

Fig. 4, conforms approximately to the surface of the cylinder having transverse ridges or corrugations 5 adapted to receive the strands of the hair between them. By preference the matrix is slightly shorter than the side bars and there is just about sufficient room between its marginal edges and the teeth 3 to receive between them the two branches 6, 6 of the retainer which will presently be described. The matrix is shifted by any suitable means, for example the pin or button 7 which rises from the back of the device and may be readily manipulated by the thumb of the user, as suggested in Fig. 6. This button may be mounted in various ways. In the present case it is fastened to a flat spring 8 which overlies the back of the frame, and at the outer end is fastened to the back of the matrix. This spring slides upon the back of the frame and on its inner side has a finger 9 capable of seating in either one of two depressions 10, 10 which are arranged at a short distance from each other longitudinally of the device, as shown in detail in Fig. 5. When the matrix is shifted to one position, said pin will seat in one of the depressions, and thereby serve to yieldingly hold the matrix against shifting. When the matrix is moved to the opposite position, the pin will seat in the other depression and yieldingly hold the matrix in that position. This mechanism may, therefore, be considered a spring locking device for yieldingly holding the matrix in the different positions to which it may be shifted.

The two branches 6, 6 of the retainer, previously mentioned, are joined at their inner end to the yoke 12 which is pivoted by a pin 13, or otherwise, to the main frame, preferably at about the point where the side bars 1 join the handle 2. The retainer is manipulated by means of a handle 14 which, when the device is in acting condition, lies parallel to and in back of the handle 2, as shown in full lines in Fig. 2. When the retainer is in non-acting position the branches 6 and handle 14 assume the position shown in dotted lines in Fig. 2.

In order to enable the hair to retain its wavy configuration, it must be subjected to heat while being worked upon. In using my device this is accomplished by heating the matrix. It is possible to heat the matrix by placing it over a gas or other flame until it attains a proper temperature. I

prefer, however, to accomplish this heating electrically, and have illustrated means by which this may be done. I place a suitable heating resistance 16 in the back of the matrix, and embed it in suitable insulating material 17. The two ends of this heating resistance are connected respectively to two conductors 18, 19 which are led out through a sleeve 20, slidably mounted within the hole 21 low main handle 2. At the inner end of this sleeve the conductors emerge in the form of an extension cord 21 through which they are electrically energized. The sleeve thus forms a sheath for the conductors. It is secured to the matrix and consequently shifts in unison with it.

In operation, after the matrix has been heated to the proper temperature, the retainer branches 6, 6 are brought to the position shown in dotted lines in Fig. 2. The strands of hair are then distributed as evenly as possible over the matrix and are led out through the teeth 3 on either side. The device is placed as near the scalp as possible for the first operation for it is preferable to work from the scalp outward toward the ends of the hair. As soon as the device has been thus positioned, the handle 14 is drawn toward the main handle 2, thus moving the retaining branches 6, 6 down upon the hair and firmly holding it in position. The device is permitted to remain thus until the strands of hair have become set or configurated, whereupon the retaining branches will be lifted sufficiently to permit the strands of hair to slip through the device but not sufficiently to permit the strands to become disengaged from or lifted out of the teeth 3. The device will then be moved bodily away from the scalp a distance approximately equal to the width of the matrix, or perhaps a little more, depending upon the effect desired. The operator will then shift the matrix longitudinally and then lower the retaining branches 6 to acting position. The parts are then permitted to remain until the portion of hair in contact with the matrix has become set or configurated, after which the process will be repeated. Ordinarily, the matrix will be shifted each time to the limit of its sliding movement upon the main frame, for example, if the first heating of the hair is done with the matrix in the position shown in full lines in Fig. 1, the second heating will be done with the matrix in the position shown in dotted lines in Fig. 1. It will be understood, however, that this is a matter of choice, for if desired the operator may shift the matrix only part way each time and cause the matrix to maintain its position by holding the thumb upon the button 7.

By proceeding in the manner above indicated, the hair may be waved with great facility, for when the strands of hair have

once been passed through the combs on either side of the device, there will be no danger of their becoming disarranged or the distribution changed. This may be rendered absolutely certain if the operator will see to it that the retaining branches 6 are not permitted to rise above the top of the comb teeth 3 after the strands of hair have once been adjusted to the device. In other words, the retaining branches may be lifted slightly to permit the device as a whole to be shifted bodily away from the scalp, and so long as said branches are not permitted to rise above the points of the teeth, there will be no opportunity for the strands of hair to escape. Hence, the teeth act as guides for the strands and in this, their effect is supplemented by the action of the retaining branches. The action of the device is automatic to such a great extent and it is so readily manipulated by one hand, that it may be used by persons having little skill, and may be used by a person to do her own hair. Furthermore, the operator is afforded a wide choice as to the final appearance of the hair, because she has a choice both as to the distance that she will move it away from the scalp each time and the distance to which she will shift the matrix each time. It will be readily appreciated that by varying these two factors, a great variety of results may be obtained.

Having thus described my invention, what I claim as new and desire to secure by Letters Patent, is:

100

1. A hair waver having a substantially flat frame adapted to lie flatwise to the head of the user, and a configurating matrix capable of engaging the strands of hair, said matrix being movable in a direction parallel to the plane of the frame.

105

2. A hair waver having a substantially flat frame adapted to lie flatwise to the head of the user, said frame having means arranged along the edges for engaging the strands of the hair, and means between the edges of the frame adapted to engage said strands, said means being movable relatively to the frame and parallel to the plane of the frame and in a direction transverse to the strands of hair.

110

3. A hair waver having a main frame with two parallel rows of upstanding comb teeth adapted to engage strands of hair leading across from one row to the other, and a configurating element for the hair arranged between said rows of teeth, said configurating element being shiftable in a direction parallel to said rows.

115

4. A hair waver having two parallel rows of upstanding comb teeth forming combs, a hair-configurating element slidably in a direction parallel to said combs, and means for retaining the strands of hair in contact with said configurating element.

120

125

130

5. A hair waver having a main frame having two opposite edges adapted to engage the strands of hair, a convex matrix arranged between said edges and also adapted 5 to engage the strands of hair, a bifurcated retainer having branches arranged between the matrix and each of the said edges of the frame, and means for producing relative movement between the matrix and the 10 frame. 6. A hair waver having a main frame, two parallel rows of teeth projecting from the front of said frame, a matrix slideable upon said frame in a direction parallel to the rows 15 of teeth, said matrix being located between said rows of teeth and presenting a convex surface at the front, said matrix having ridges or corrugations arranged transversely to the rows of teeth for engaging the strands 20 of hair, and means for releasably holding the hair in contact with the matrix while the hair is being configurated. 7. A hair waver having a main frame provided with a main handle, two parallel rows 25 of teeth projecting from the front of said frame, a matrix shiftable upon the frame in a direction parallel to the rows of teeth, said matrix having a convex front surface, a bifurcated retainer for the hair, said retainer 30 being pivoted to the main frame and having two branches, one adjacent to each row of teeth, and a handle for operating said retainer. 8. A hair waver having a main frame provided with a main handle, a shiftable matrix 35 on said frame, a row of comb teeth on either side of said matrix, a bifurcated retainer adapted to engage the strands of hair along lines adjacent to each row of teeth, said retainer being pivoted to the main frame, and a handle for said retainer adapted to come approximately parallel to the main handle on the side thereof opposite to the side where the acting portion of the retainer is located. 9. A hair waver having a main frame provided with parallel rows of teeth, a matrix 45 slideable on said main frame between said rows of teeth, and an electric heating element mounted upon said matrix, and slideable therewith. 10. A hair waver having a main frame, means on said main frame for preventing the strands of hair shifting in a direction longitudinally of the frame, a matrix shiftable longitudinally on said frame, a hollow 50 handle for supporting said frame, an electric heating element mounted upon said matrix and shiftable therewith, and a sleeve slideable within the hollow of said handle in unison with the matrix for conducting electric wires 55 through said handle and protecting them during the sliding movement of the wires and matrix. 11. A hair waver having a main frame, parallel combs on said frame for preventing the strands of hair shifting in a direction longitudinally of the frame, a matrix shiftable longitudinally on said frame and located between said combs, a retaining element for holding the strands of hair in engagement with the teeth of the comb, and means shiftable in unison with said matrix 60 for heating it. 12. A hair waver having a main frame, parallel combs projecting from the front of 65 said frame for preventing the strands of hair shifting in a direction longitudinally of the frame, a matrix shiftable longitudinally on said frame and located between said combs, said matrix presenting a convex surface at the front of the device, a retaining element for holding the strands of hair in engagement with the teeth of the comb, and locking means for yieldingly holding the 70 matrix against shifting. 85

In witness whereof, I have hereunto subscribed my name.

MABEL A. C. HENDERSON.
